UNITED STATES PATENT OFFICE.

HENRY J. SCHMICK, OF WILLIAMSPORT, PENNSYLVANIA, ASSIGNOR TO SCHMICK SCREW AND GEAR COMPANY, OF WILMINGTON, DELAWARE, A CORPORATION OF DELAWARE.

SCREW JACK.

Application filed May 10, 1921. Serial No. 468,256.

To all whom it may concern:

Be it known that HENRY J. SCHMICK, a citizen of the United States, residing at Williamsport, county of Lycoming, State 5 of Pennsylvania, has invented an improvement in Screw Jacks, of which the following description, in connection with the accompanying drawings, is a specification, like characters on the drawings representing like 10 parts.

This application is a continuation in part of applicant's prior applications filed November 12, 1920, Serial No. 423,693 and Serial No. 423,694, for improvements in 15 screw jacks and lifting jacks, respectively.

This invention aims to improve and simplify the construction, increase the durability, and lessen the manufacturing cost of portable jacks, particularly such as are 20 used for automobiles, although it is not restricted to such jacks.

The invention further aims to promote rapidity and ease of operation, and to protect the operating parts from dirt and keep 25 them lubricated ready for use at all times.

The jack shown in the drawings is an illustrative embodiment of the invention and illustrates a preferred means of attaining its objects.

30 In the drawings, Fig. 1 is a side elevation of a screw jack showing the top section or casing in partly raised position;

Fig. 2 is a cross-section of the same on the line 2—2 in Fig. 1;

35 Fig. 3 is a vertical central section of the jack showing the operating gears, ratchet and screw in side elevation;

Fig. 4 is a sectional view of the top part of the jack; drawn to a larger scale, showing 40 the construction of the ratchet and friction device for holding the jack in raised position under load; and

Fig. 5 is a perspective view of the hollow base member.

45 Referring to Figs. 1 and 2, the jack shown therein has a base 11 supporting a hollow pillar or body 12 upon which the top or casing section 13 is arranged to slide up and down. The body has two arms or 50 lengthwise guides 14 formed upon its exterior, and the casing 13 has corresponding grooves 15 fitting the guides. The inner and outer surfaces of the body and casing are left rough except for these guides and

grooves, which are machined to slide easily 55 and maintain coaxial and angular alignment of the parts in all positions of the jack.

Referring more particularly to Fig. 3, the hollow body 12 has a series of partial 60 screw threads 16 cast on each half of its inner surface to receive the jack screw 17. These series of threads extend from top to bottom of the body and the spaces between their ends form two diametrically opposed 65 grooves likewise extending from top to bottom of the body. This formation enables the body to be made of cast iron, thereby cheapening its cost.

The stem 18 of the screw projects out of 70 the top of the body and carries a bevel gear 19 near its upper end. A mating gear 20 carried by a shaft 21 journaled in the casting affords a means of rotating the screw 17 in either direction. The jack may be raised 75 and lowered by turning a handle 22, suitably connected to the shaft 21, to permit of its being removed and folded up. The handle also affords convenient means for carrying the jack and for positioning it under the 80 axle of an automobile or other thing to be lifted.

Referring more particularly to Fig. 4, a combined friction and thrust plate 23 is arranged to turn on the top end of the 85 stem 18 of the screw. This plate is adapted on its upper side to engage against the under side of the top part 24 of the casing. The plate 23 has a central hub 25 which projects into a circular recess in the under 90 side of the top 24 in line with the axis of the screw. The hub is hollow to receive the upper end of the stem 18. The hub 25 has a solid top end, and contains a thrust ball 26 against which the upper end of the screw stem 18 bears, thereby providing an 95 effective anti-friction bearing not easily cramped by uneven loading and capable of carrying a heavy load. A steel plug or button 27 is set in the top end of the stem 18 100 for the ball to bear on.

The plate 23 has a circle of ratchet teeth 28 on its under side, and the gear 19 has a ratchet 29 held by a spring 30 to engage the ratchet teeth and cause the plate to 105 rotate when the screw is turned to lower the jack. The ratchet slides over the teeth when the screw is turned to raise the jack.

The plate 23 is left rough except for the hub and the top surface, which are machined to fit the under side of the top 24 of the casting, which is also machined at the places 5 where the plate touches it.

A cover 31 is secured to the top over the opening for the gear 19; and a cover 32 having a bearing for the shaft carrying the operating gear 20 is also secured to the top. 10 The covers may be removed to give access to the gearing and ratchet, and for adding grease to them.

The top part 24 of the casing is formed with a central post or support 33 and a 15 step 34 at one side of the post for engaging under the article to be lifted. A removable extension post 35 is also provided for lengthening the jack in case of need.

To operate the jack the handle 22 is 20 rotated to raise or lower the screw 17 in the body 12. If the screw is turned to raise the body the ratchet slides over the teeth on the plate 23, and permits free rotation. If the screw is turned to lower the body the 25 ratchet will engage in the ratchet teeth and turn the plate against whatever friction may be occasioned by the load. The resistance to turning is greater with larger loads, thereby preventing the screw from being 30 forced down by the load.

The construction of the casing and operating parts of the jack is simple and strong, the design being such that cast iron may be used for all of the principal parts and 35 very little machine work is required to finish them. The working parts are all encased and adequate provision is made for insuring proper lubrication of the thread and screw.

40 The invention is not restricted to the details of construction shown and described.

I claim the following as my invention:

1. A screw jack comprising a casing having its interior threaded from end to end, 45 a screw of coarse pitch engaging said thread, said screw having a short threaded portion at its lower end of large diameter and a long stem projecting from said casing, means on said casing for guiding said stem and 50 means carried by said stem for rotating said screw.

2. A screw jack provided with a screw having a short threaded portion of large 55 diameter and a long stem, a barrel nut constituting the body of said jack and enclosing said screw and stem, means slidable on the exterior of said barrel nut for guiding the extremity of said stem, a bearing sleeve carried by said guiding means, a thrust 60 bearing between said sleeve and stem, and means carried by the stem for rotating said screw.

3. A screw jack comprising an enclosing 65 casing having an open end, a hollow cylinder within said casing with one end projecting

from said open end, said casing and cylinder being arranged to telescope, the inner walls of said cylinder having partial screw threads and a screw arranged in the cylinder and engaging said threads, whereby a 70 communication is provided for between the spaces within said cylinder on either side of said screw, said screw having a swivel connection with said casing, and means in said casing for operating said screw, said 75 operating means being entirely encased whereby dirt is prevented from reaching said operating means and screw, and lubricant is retained in the cylinder in proximity to the operating parts.

4. In a screw operated jack, a screw having a stem, a barrel nut enclosing the screw and major part of the stem and having interrupted threads, said barrel nut having a closed base, a casing swiveled to said stem and enclosing said nut, the space within said casing and nut being adapted to contain lubricant, and actuating means for said screw housed within said casing.

5. In a screw operated jack, a screw having a stem, a barrel nut enclosing the screw and major part of the stem and having interrupted threads, said barrel nut having a closed base, a casing swiveled to said stem and enclosing and sliding on said nut, the 95 space within said casing and nut being adapted to contain lubricant, spaces between the ends of said threads for permitting lubricant to circulate, and actuating means for said screw housed within said casing.

6. A screw jack having a screw with an angle of lead greater than the angle of repose of the thread, a casing for said screw, means for rotating said screw freely in a direction to operate said jack, and friction means between said screw and casing, effective in proportion to the load on said jack to prevent rotation of said screw in the reverse direction, said friction means having a ratchet connection with said rotating means, and a pawl unit for said ratchet connection comprising a cup, a detent slidable therein, and a spring in said cup bearing against said detent.

7. A screw jack comprising an enclosing 115 casing having an open end, a hollow cylinder within said casing with one end projecting from said open end, said casing and cylinder being arranged to telescope, the inner walls of said cylinder having screw 120 threads and a screw arranged in the cylinder and engaging said threads, said screw having a stem projecting from the inner end of said cylinder and journaled at its extremity in said enclosing casing, a shoulder near the extremity of said stem, and a friction member having a bearing against said shoulder, said friction member bearing against and having frictional engagement with said casing, and means within said cas- 130

ing operatively connected to said stem for rotating said screw, said rotating means having a one way operating clutch connection with said friction member preventing 5 relative rotation in one direction whereby it is frictionally held by said casing against operation to move said screw in said direction.

8. A screw jack comprising an enclosing 10 casing having an open end, a hollow cylinder within said casing with one end projecting from said open end, said casing and cylinder being arranged to telescope, the inner walls of said cylinder having screw threads and 15 a screw arranged in the cylinder and engaging said threads, said screw having a stem projecting from the inner end of said cylinder, a friction member having a bearing against said projecting end, said friction member bearing against and having 20 frictional engagement with said casing, a ratchet on said friction member and a pawl rotatable with said stem and engaging said ratchet, said pawl permitting free rotation 25 of said stem with respect to said friction member in one direction, and preventing relative rotation thereof in the opposite direction.

9. A screw jack having an operating 30 screw, tubular casing sections slidably arranged one within the other to enclose the screw, the inner section having an internal screw thread and external guides formed integral therewith, and the outer section 35 having internal guides fitting said external guides to position the sections concentrically and prevent relative rotation.

10. A screw jack having an operating screw with a long stem, tubular casing sections 40 slidably arranged one within the other to enclose the screw, the inner section having an internal screw thread and external guides formed integral therewith, and the outer section having internal guides fitting 45 said external guides to position the sections concentrically and prevent relative rotation, and means carried by said outer section for rotating the screw and guiding its stem.

11. A screw jack having an operating 50 screw with a long stem, tubular casing sections slidably arranged one within the other

to enclose the screw, the inner section having an internal screw thread and external guides formed integral therewith, and the outer section having internal guides fitting 55 said external guides to position the sections concentrically and prevent relative rotation, and means for rotating the screw and guiding its stem, said means comprising a device for restraining said screw against rotation 60 in one direction without interfering with its freedom of rotation in the opposite direction.

12. A screw jack having a screw with a stem, a thrust member having a hub encircling said stem, the extremity of said hub being closed over the end of said stem, and an antifriction ball bearing between the end 65 of said stem and the extremity of said hub.

13. A screw jack having a screw with a 70 stem, a thrust member having a hub encircling said stem, the extremity of said hub being closed over the end of said stem, a hardened steel pin inserted at the end of said stem, and an antifriction ball bearing 75 between the end of said stem and the extremity of said pin.

14. As a new article of manufacture, a portable screw jack having a base and tubular body supported thereby, said body having 80 screw threads cast on its inner wall for its entire length, said screw threads being interrupted by two diametrically opposed grooves running lengthwise of said body from end to end, a cast metal screw having 85 a short threaded end portion and a long stem extending out from the upper end of said body, a casing closed at its top and surrounding said body, said body and casing having guides and grooves integral therewith for maintaining said casing in axial and angular alignment with said body, a hub on said casing to receive the end of said screw, a ball thrust bearing between the end 90 of said screw and said hub, and means carried by said casing for rotating said screw in either direction and for frictionally holding it against rotation in one direction.

In testimony whereof, I have signed my name to this specification.

HENRY J. SCHMICK.
